JOSEPH OSTRAK, OF ST. LOUIS, MISSOURI

ELECTRICAL HEAT PRODUCING ELEMENT

Application filed January 18, 1929. Serial No. 333,347.

This invention relates generally to electrical heat producing elements of the type which includes as a part thereof a high resistance electrical conductor, and has for its principal object the production of such a heat producing element which is provided with improved means whereby the heat produced by the high resistance conductor may be distributed over a relatively wide area instead of being confined to the area of the electrical conductor as heretofore.

Prior to this invention the electrical heat producing units with which I am familiar included each a resistance conductor which, when the unit was in operation, emitted heat. These resistance conductors were usually in the form of single wires of relatively small diameter, and hence the heat producing areas thereof were quite limited. The main purpose of the present invention is to increase the effective heat producing areas of the heat producing elements, and this purpose is accomplished by associating with the resistance conductors plate-like members of substantial area to which heat is transmitted by the said resistance conductors. Because of this arrangement the heat produced by the resistance conductors is distributed over a substantially greater area than heretofore, whereby the effectiveness of the heat producing elements is increased.

Fig. 1 illustrates a fragmentary view of a casing or housing constructed in accordance with my invention.

Figs. 2, 3, 4, and 5 illustrate the principle of my invention applied to heat distributing elements of various shapes.

Fig. 6 is an enlarged fragmentary perspective of the heat producing unit, several of which are shown in association with the end walls of the casing shown in Fig. 1.

Fig. 7 is an enlarged fragmentary perspective illustrating the arrangement shown in Fig. 4.

Fig. 8 is an enlarged fragmentary perspective illustrating the arrangement shown in Fig. 5.

In the drawings, wherein is illustrated one embodiment merely of the invention, and referring particularly to Fig. 1 thereof,

A designates a casing or housing, which may, for instance, be a heating or drying element of some sort, the portion of said casing or housing which is illustrated including a side wall B and the opposite end walls C thereof. The side wall B of the casing or housing A illustrated in Fig. 1 is provided with a plurality of recesses 1 spaced longitudinally of said side wall, each of said recesses being substantially U-shaped and comprising a pair of spaced side walls 2 which are joined together by a curved bottom wall 3.

Arranged within each of the recesses 1 is a high resistance electric wire 4, said wire 4 being extended longitudinally of said recess. The wall B of the casing A may be formed of a metal which is a conductor of electricity, and when this is so I associate with each high resistance wire an electrical insulating element 5. The insulating elements 5 serve to prevent the passage of electrical energy from the various resistance wires 4 to the wall B of the casing or housing, but these insulating elements are not heat insulators and hence do not prevent the passage of heat from the resistance wires 4 to the wall B. It will be noted that the insulating elements 5 are of substantially the same shape as the recesses 1; that is to say, each insulating element is substantially U-shaped and the wall portion thereof is interposed between the outer surface of the associated resistance wire and the inner face of the recess.

Because of the arrangement of the resistance wires within the U-shaped recesses 1, it is plain that a greater portion of outer surface of each resistance wire is in close proximity to the wall of the U-shaped recess 1 in which said resistance wire is positioned, hence most of the heat emitted from the resistance wire will be transmitted to the walls of the recess. The walls of the recesses 1 are associated with wall portions B', which are of substantial area and to which heat transmitted to the walls of the recesses by the resistance wires passes, hence said heat is distributed over a substantially wide area instead of being confined to the relatively small area of the resistance wires as heretofore.

The end walls C of the casing or housing

A are provided with a plurality of straps 6, which are rigidly attached thereto as shown in Figs. 1 and 6. When viewed in plan or horizontal section, the portion of each strap 6 intermediate of the side edges thereof which are secured to the associated wall C is spaced apart from the face of the wall C to which the strap is attached, to provide a space in which a high resistance wire 4 and an insulating element 5 are positioned in the manner in which the resistance wires and insulators are associated in the U-shaped recess 1 formed in the side wall B of the casing or housing A. The resistance wires and insulators associated with the strap 6 extend longitudinally of the spaces within said straps, and because the greater portion of the outer surface of each of said resistance wires is arranged in close proximity to the walls of the straps 6 and to the end walls C of the casing or housing A, most of the heat emitted from said resistance wires will be transmitted to the straps and end wall C, whereby said heat will be distributed over substantial area.

In Figs. 2, 3, 4 and 5 my improved heat producing arrangement is shown in association with heat distributing elements of various shapes. However, in each of these forms of the invention the resistance wires and the insulators associated therewith are positioned within U-shaped recesses.

In Fig. 2 the heat distributing element comprises a circular wall B^a, which joins the walls of the U-shaped recesses being extended inwardly with respect to said circular wall B^a.

In Fig. 3 a heat distributing element B^b is illustrated with respect to which U-shaped recesses 1^c extend outwardly.

The heat distributing element shown in Fig. 4 comprises a substantially diamond-shaped figure, the wall portions B^d of said element which connect the walls of the U-shaped recess 1^d being straight instead of curved, as in Figs. 2 and 3.

In Fig. 5 the heat distributing element in cross-section comprises a simple elongated loop B^e and the resistance wires and insulators are positioned in the U-shaped recesses 1^e provided at the opposite ends of said loop.

In all of the forms of the invention illustrated it will be noted that the wall portions of the heat distributors to which heat is transmitted by the resistance wires are arranged in close proximity to said resistance wires on a plurality of sides thereof. Because of this arrangement it is plain that most of the heat will pass directly from the resistance wires to the walls of the heat distributors whereby very little heat emitted from said resistance wires will be lost.

When the wall portions of the heat distributing elements are formed of material which is a non-conductor of electricity, the insulators 5 may, of course, be dispensed with.

I claim:

A heat producing unit comprising a high resistance electric conductor, a heat distributing element associated with said high resistance conductor, said heat distributing element being of greater area than said high resistance conductor and being provided with a substantially U-shaped recess in which said high resistance conductor is positioned in a manner to cause wall portions of the recess to be in close proximity to a plurality of sides of said high resistance conductor, and a substantially U-shaped electric insulating element interposed between said high resistance conductor and portions of the wall of said recess, said recess being of a depth which is substantially greater than the corresponding dimension of the electric conductor, whereby the heat distributing area of the walls of said recess is increased.

In testimony that I claim the foregoing I hereunto affix my signature.

JOSEPH OSTRAK.
